UNITED STATES PATENT OFFICE.

CHARLES E. NOLTING, OF LITTLE ROCK, ARKANSAS.

AUTOMOBILE RADIATOR SUPPORT.

Application filed May 25, 1921. Serial No. 472,378.

To all whom it may concern:

Be it known that I, CHARLES E. NOLTING, a resident of Little Rock, in the county of Pulaski and State of Arkansas, a citizen of the United States, have invented certain new and useful Improvements in Automobile Radiator Supports, of which the following is a specification.

The object of this invention is to provide means for holding an automobile radiator in a desired position while it is being repaired or tested.

A further object of the invention is to provide a holder which may be conveniently adjusted to change the position of the radiator, and a further object is to provide a holder which may be easily adjusted to accommodate large or small radiators and will securely hold the radiator upon which work is to be done.

A still further object of the invention is to provide means whereby a radiator may be readily moved into or out of a testing tank, and another object is to provide means whereby a lamp may be arranged to throw its light directly upon the radiator in any and all positions of the holder.

Other incidental objects of the invention will appear in the course of the following description.

One embodiment of the invention is illustrated in the accompanying drawings, in which—

Fig. 1 is a perspective view of the apparatus;

Fig. 2 is a plan view, partly in section, showing a radiator by dotted lines within the testing tank; and

Fig. 3 is a perspective view showing a small radiator held in an upright position.

In the drawings 1 denotes the testing tank, which may be of any preferred or convenient form and construction and, in use, is filled with liquid to the proper level. Upon one corner of the tank I secure upper and lower brackets 2, in each of which is a pair of spaced circumferentially grooved rollers 3, and passing between and guided by said rollers is a standard 4, which constitutes a portion of a goose neck carrier and is circular in cross section in order that it may readily turn about its own longitudinal axis between the rollers as bearings. The lower end of this standard rests upon one end of a setting lever 5, and is preferably enlarged, as at 6, to reduce its liability to slip off the

lever. The lever is fulcrumed between its ends on a bracket 7, projecting from the side of the tank and, near its power end, a locking plate 8 is secured upon the lever in position to ride over and engage the teeth of a ratchet bar 9, secured vertically upon the side of the tank. It will be readily understood that the operation by foot pressure upon the lever may raise the standard 4 to any desired height and the locking plate 8 by its engagement with the ratchet 9 will hold the standard in its set position. A slight lateral pressure on the power end of the lever will release the locking plate from the ratchet and permit the standard to be lowered.

The upper end of the standard 4 is connected by a return bend with a hanger member 11, which extends downwardly parallel with the standard and terminates in a lateral arm 12, disposed approximately midway the height of the standard. The end of the lateral arm carries a split sleeve 13, which is aligned axially with the arm, and, in the present instance, is connected with the arm by a coupling 14. A stud 15 is rotatably received in the socket 13 and is held in a set position by the headed clamping screw or bolt 16 engaged in ears on the sleeve at the sides of the split therein in a well known manner. The outer end of the stud 15 has a head 17, and in this head is fitted the lower shouldered circular end of a post 18, which is equipped with a binding screw 19, having a lever handle whereby, when the screw is turned home, the post will be clamped in any position in which it is set, it being understood that the post may be turned in the head about its own longitudinal axis to vary the position of the carrier bar 20 which is rigid with the upper end of the post. The carrier bar 20 is preferably integral with the upper end of the post and it extends in opposite directions therefrom. In the ends of the bar, which are split, are fitted extension bars 21, which are secured in the positions to which they may be adjusted by the clamp screws 22. Transverse rests 23, are provided on the carrier bar 20, at the ends thereof, and similar rests 24 are provided on the extension bars 21. The extremities of the extension bars are slotted and stems 25 are fitted through the slits or splits, and adjustably secured by the clamp screws 26. The upper ends of the stems 25 are turned laterally and terminate in internally thread-

ed eyes 27, through which are engaged the screws 28 carrying clamping plates 29 at their lower ends.

On the return bend 10 is pivotally mounted a collar 30, from which extends an arm 31, and to this arm is pivoted one end of one of a series of pivotally connected links 32, the outermost link carrying an electric lamp 33.

10 The radiator to be tested or repaired is disposed flat upon the rests 23 and 24 and the stems 25 are turned so as to bring the clamping plates 29 over the radiator and secured, the screws 28 being then turned 15 home so that the radiator will be firmly clamped between the plates 29 and the rests 24. If the radiator be large, the extensions 21 are drawn out the proper distance, as shown in Fig. 1, but a small radiator will be held 20 without drawing out the extensions, as shown in Fig. 3. The stems 25 are rotatable in the extremities of the extensions so that the screws 28 will be out of the way when a radiator is being removed or brought 25 into place, and the members 15, 17 and 18, constitute a universal joint permitting the radiator to be brought into any desired position with either side or either end up, and the foldable or extensible form of the lamp 30 carrier obviously permits the lamp to be arranged so as to throw its light upon any desired point of the radiator. When the radiator is to be submerged the lever 5 is manipulated to lift the gooseneck carrier so 35 that the radiator will be raised above the level of the top of the tank after which the carrier and the radiator are pushed manually to a position over the tank. The lever is then manipulated to permit descent of 40 the carrier and the radiator to effect partial or complete submergence of the radiator. Reversing the operation will withdraw the radiator from the tank.

Having thus fully described my invention, 45 what I claim as new and desire to secure by Letters Patent of the United States, is—

1. The combination of a tank, a carrier supported on the tank, a carrier bar on the carrier, and means connecting the carrier 50 bar and carrier whereby the carrier bar may be moved pivotally in both vertical and horizontal planes without movement of the carrier.

2. The combination with a vertically and 55 horizontally movable carrier, of a carrier

bar, means for clamping work upon said carrier bar, and a universal connection between said bar and the carrier.

3. The combination of a tank, brackets secured thereto, a vertically and horizontally movable carrier mounted in said brackets, of a carrier bar, means for clamping work upon said bar and a universal connection between said carrier bar and the carrier. 60

4. The combination with a vertically and horizontally movable carrier, of a carrier bar, means for clamping work upon said bar, a universal connection between said carrier bar and the carrier, and a foldable and extensible lamp holder mounted on the 70 carrier above the carrier bar. 65

5. The combination of a tank, upper and lower pairs of peripherally grooved rollers mounted on the tank, a goose neck carrier having a standard passing between the 75 rollers of each pair of rollers, and a vertically movable support for said standard mounted on the tank. 75

6. The combination of a tank, upper and lower roller bearings on the tank, a lever 80 fulcrumed on the tank, a carrier including a standard passing vertically through said bearings and having its lower end resting on one end of said lever, a vertical ratchet on the tank adjacent the opposite end of the 85 lever, and a locking plate on the lever engaging said ratchet. 80

7. The combination of a carrier, a carrier bar mounted on the carrier, extensions adjustably secured to the ends of said carrier 90 bar, rests on the carrier bar and the extensions and means for clamping work to said rests. 90

8. The combination of a carrier, a carrier bar mounted thereon, rests on said bar, rotatably and longitudinally adjustable stems at the ends of said bar, and clamps carried by said stems to secure work against the 95 rests. 95

9. The combination of a carrier including 100 a horizontal arm, a socket in the end of said arm alined axially therewith, a stud rotatably fitted in said socket, a post rotatably fitted in the end of said stud and transverse thereto, a carrier bar fixed to 105 said post, and means for securing work to said bar. 100

In testimony whereof I hereunto affix my signature.

CHARLES E. NOLTING.
